US00D776782S

(12) **United States Design Patent** (10) Patent No.: **US D776,782 S**
Pedersen (45) Date of Patent: ** Jan. 17, 2017

(54) BROADHEAD ARROWHEAD HAVING BOTH EXPANDABLE AND FIXED CUTTING BLADES	3,036,396 A	5/1962	Swails
	3,064,977 A	11/1962	Zwickey
	3,138,383 A	6/1964	McKinzie
	3,527,463 A	9/1970	Turner
	3,578,328 A	5/1971	Rickey
(71) Applicant: Out RAGE, LLC , Cartersville, GA (US)	3,618,948 A	11/1971	McGlocklin
	3,653,664 A	4/1972	Gentellalli
	3,672,677 A	6/1972	Moore
(72) Inventor: William E. Pedersen , Duluth, MN (US)	3,738,657 A	6/1973	Cox
	3,741,542 A	6/1973	Karbo
	3,756,600 A	9/1973	Maleski
	3,759,519 A	9/1973	Palma
(73) Assignee: FeraDyne Outdoors, LLC , Superior, WI (US)	3,824,026 A	7/1974	Gaskins
	3,854,723 A	12/1974	Wilson
	3,881,730 A	5/1975	Carella
	3,893,866 A	7/1975	Hollingsworth
	3,897,062 A	7/1975	Christensen
	3,910,579 A	10/1975	Sprandel
	3,915,455 A	10/1975	Savora
	3,941,059 A	3/1976	Cobb
	4,006,901 A	2/1977	Simo
(21) Appl. No.: 29/527,918	4,029,319 A	6/1977	Christen
(22) Filed: May 22, 2015	4,036,499 A	7/1977	Sherwin
(51) LOC (10) Cl. 22-01	4,043,020 A	8/1977	Hoggard
(52) U.S. Cl. USPC D22/107	4,055,975 A	11/1977	Serfozo et al.
(58) Field of Classification Search USPC D22/107, 115	4,082,292 A	4/1978	Fletchic et al.
	4,093,230 A	6/1978	Simo
	4,099,720 A	7/1978	Zeren
	4,141,554 A	2/1979	Sherwin
	4,146,226 A	3/1979	Sorensen
	4,166,619 A	9/1979	Bergmann et al.
	4,203,601 A	5/1980	Simo
	4,210,330 A	7/1980	Kosbab
(56) References Cited	4,212,463 A	7/1980	Repinski et al.
	4,234,191 A	11/1980	Erlandson
	4,254,958 A	3/1981	Bateman, III
	4,341,391 A	7/1982	Anderson
	4,381,866 A	5/1983	Simo
	4,405,133 A	9/1983	Cartwright, Jr.
	4,410,184 A	10/1983	Anderson
	4,452,460 A	6/1984	Adams
	4,504,063 A	3/1985	LeBus
	4,505,482 A	3/1985	Martin, Sr.
	4,529,208 A	7/1985	Simo
	4,534,568 A	8/1985	Tone
	4,558,868 A	12/1985	Musacchia
	4,565,377 A	1/1986	Troncoso, Jr. et al.
	4,576,589 A	3/1986	Kraus et al.
	4,579,348 A	4/1986	Jones
	4,601,710 A	7/1986	Moll
	4,615,529 A	10/1986	Vocal
	4,616,835 A	10/1986	Trotter
	4,621,817 A	11/1986	Musacchia

CLAIM

The ornamental design for a broadhead arrowhead having both expandable and fixed cutting blades, as shown and described.

DESCRIPTION

FIG. 1 is a front view of an expandable broadhead with: a) a ferrule, as shown in FIGS. 18-23, having four fixed blades and a chisel tip with straight cutting edges; b) two expandable blades; and c) a first shock collar retaining the two expandable blades in a retained position;
FIG. 2 is a perspective view of FIG. 1;
FIG. 3 is an exploded perspective view of FIG. 1;
FIG. 4 is a top view of FIG. 1;
FIG. 5 is a front view of the expandable broadhead of FIG. 1, with the two expandable blades in a fully deployed position;
FIG. 6 is a perspective view of FIG. 5;
FIG. 7 is a top view of FIG. 5;
FIG. 8 is a front view of an expandable broadhead with: a) a ferrule, as shown in FIGS. 18-23, having four fixed blades and a chisel tip with straight cutting edges; b) two expandable blades; and c) a second shock collar retaining the two expandable blades in a retained position;
FIG. 9 is a perspective view of FIG. 8;
FIG. 10 is an exploded perspective view of FIG. 8;

FIG. 11 is a front view of an expandable broadhead with: a) a ferrule, as shown in FIGS. 24-29, having four fixed blades and a chisel tip with spiral cutting edges; b) two expandable blades; and c) a second shock collar retaining the two expandable blades in a retained position;
FIG. 12 is a perspective view of FIG. 11;
FIG. 13 is an exploded perspective view of FIG. 11;
FIG. 14 is a top view of FIG. 11;
FIG. 15 is a front view of the expandable broadhead of FIG. 11, with the two expandable blades in a fully deployed position;
FIG. 16 is a perspective view of FIG. 15;
FIG. 17 is a top view of FIG. 15;
FIG. 18 is a side view of an expandable broadhead ferrule, as shown in FIGS. 1-10, with four fixed blades and a chisel tip with straight cutting edges;
FIG. 19 is a cross section view taken along the line 19-19 as shown in FIG. 18;
FIG. 20 is a cross section view taken along the line 20-20 as shown in FIG. 18;
FIG. 21 is a cross section view taken along the line 21-21 as shown in FIG. 18;
FIG. 22 is a cross section view taken along the line 22-22 as shown in FIG. 18;
FIG. 23 is a cross section view taken along the line 23-23 as shown in FIG. 18;
FIG. 24 is a side view of an expandable broadhead ferrule, as shown in FIGS. 11-17, with four fixed blades and a chisel tip with spiral cutting edges;
FIG. 25 is a cross section view taken along the line 25-25 as shown in FIG. 24;
FIG. 26 is a cross section view taken along the line 26-26 as shown in FIG. 24;
FIG. 27 is a cross section view taken along the line 27-27 as shown in FIG. 24;
FIG. 28 is a cross section view taken along the line 28-28 as shown in FIG. 24; and,
FIG. 29 is a cross section view taken along the line 29-29 as shown in FIG. 24.
